RUDOLPH W. GLASNER AND FREDRICH J. RODE, OF CHICAGO, ILLINOIS

CUSHION FOR SHEET METAL PRESSES

Application filed April 12, 1930. Serial No. 443,904.

In hydraulic cushioning devices for sheet metal presses for resisting the movement of the pressure pad in one direction, means have been provided for overcoming the shock 5 caused by the sudden resistance of the liquid to the movement of the piston element, and check and relief valves have also been provided but they have been usually arranged as separate elements and have embodied a more or less complicated structure.

It is one of the objects of the present invention to simplify the construction of such cushions by incorporating the relief valve, check valve and shock absorber in one unit.

A further object is to provide improved means for compensating the variation of pressure in the cushion by varying the pressure on a column of liquid which in turn is effective upon a piston operating in a cylinder immediately below and in communication with the pressure accumulator reservoir.

A further object is to provide a combined shock absorber and relief valve, which latter will not operate until substantially the limit of the stroke of the shock absorbing element has been reached, at which time the relief valve will operate and will also serve as a check valve which permits liquid to flow into the cushion cylinder and thereby cause the latter to be maintained filled at all times, the valve operating as a check to prevent the escape of liquid from the cushion cylinder until a predetermined time in the cycle of operation of the mechanism.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention, and in which

Figure 1 is a view partly in elevation and partly in section of a sheet metal press having a cushioning device constructed in accordance with the principles of this invention used in connection therewith, and with the parts in one position.

Figure 2 is a view similar to Figure 1, with parts omitted, and showing the parts in another position.

Figure 3 is an enlarged detail sectional view of the combined shock absorber, check 55 and relief valve showing the parts in the position which they assume at substantially the limit of the movement of the shock absorbing device in one direction.

Referring more particularly to the drawings, the numeral 10 designates the base of the press, 11 uprights, 12 a crank shaft which receives its motion from any suitable source, 13 a reciprocating ram which is connected with the crank shaft by means of links 14, 60 and which ram reciprocates upon the uprights 11, and 15 a die connected to the ram.

Mounted upon the bed 16 is a die 17 with which the die 15 co-operates, and 18 designates a work holding member or clamp that 70 co-operates with the die 15. The work holder is supported by means of suitable pins 19 which pass through the bed 16 of the press and engage and are supported by a pressure pad 20, the latter being resisted in its movement by means of a piston 21 operating in the cylinder 22.

All of the above referred to parts are of the ordinary and well known construction.

The pad 20 is yieldingly resisted in its 80 movement by means of a liquid column preferably in the form of a pipe or conduit 23 which has communication with the cylinder 22.

Connected with the pipe 23 and mounted 85 preferably upon a suitable base 24 and communicating with the pipe 23, is a bearing member 25 forming an extension of the pipe or conduit and in which bearing member a plunger 26 operates. Connected to the 90 plunger 26 is a piston 27 which is recipro-
cable in a cylinder 28, the latter being supported preferably from the base 24 by means of uprights or standards 29. Superposed upon the cylinder 28 is a pressure accumu- 95 lator tank or reservoir 30 which has communica-
tion with the cylinder 28. This reservoir 30 is provided with a closure 31 and receives fluid under pressure, such as air or the like 100 through a supply pipe 32 from a suitable

source, a pressure regulating valve 33 being arranged in the pipe and a pressure gage 34 is also provided for the reservoir 30.

6 A gage glass 35 may also be provided for the cylinder 20.

A suitable packing 36 is provided to form a fluid tight joint between the plunger 26 and the bearing member 25.

The plunger 26 is hollow as at 37 and one 10 end thereof is shaped to form a valve seat 38 with which a valve 39 co-operates. Connected with the valve is a stem 40 of a diameter considerably less than the internal diameter of the plunger 26. The valve stem passes 15 through suitable bearings 41 in the plunger and extends for a considerable distance beyond the piston 27 and into the cylinder 28, a nut or collar 42 being provided on the end of the valve stem and a spring 43 encompasses 20 the valve stem with one end abutting the collar 42 and the other end resting upon the bearing 41. The normal tendency of the spring 43 is to close the valve 39 by holding the same upon its seat 38.

25 Arranged within the cylinder 28, preferably to extend thereacross and within the path of movement of the end of the valve stem 40, is an abutment 44 which, when the piston 27 and plunger 26 approach the limit 30 of their movement in one direction, will be contacted by the end of the stem 40 and the valve 39 will be opened against the stress of the spring 43.

The bearing member 25 is provided with a 35 reduced interior portion adjacent one end thereof to form a shoulder 45, for a purpose to be set forth.

Liquid is supplied to the cylinder 22 and the cylinder 28 in any suitable manner (not 40 shown) and fluid pressure such as air pressure is supplied to the reservoir 30 through the pipe 32.

The normal position of the parts are as shown in Figure 1, that is with the pressure 45 pad 20 abutting the lower face of the bed 16 of the press and the piston 21 at the limit of its return movement in the cylinder 22, and one end of the plunger 26 will engage and rest upon the shoulder 45 in the bearing member 25 while the spring 43 will hold the valve 39 closed. The predetermined resistance pressure is maintained in the reservoir 30 and will act upon the liquid in the cylinder 28 to hold the piston 27 in its lower- 55 most position, and the plunger 26 against the shoulder 45, when the ram of the press 13 is in an elevated position.

When the ram descends and the die 15 cooperates with the work holder 18 to operate 60 upon the work 46, the pressure pad 20 will be lowered in the cylinder 22 to create a pressure upon the liquid column confined between the piston 21, the end of the plunger 26 and the valve 39.

65 As soon as the piston starts to move down-

wardly there will be an initial resistance of the liquid against the piston, which has a tendency to cause a shock to the mechanism.

In order to overcome this initial shock the plunger 26 and piston element 27 are provided. As soon as pressure is created upon the liquid in the column the pressure will be conveyed through the liquid column to the valve 39 and end of the plunger 26, causing the same to rise from the position shown in Figure 1 to the position shown in Figure 2 and the piston 27 and plunger 26 will continue to rise until the end of the valve stem 40 contacts with the abutment 44 (see Figure 3), after which a continued movement of the plunger 26 and piston 27 in the same direction will cause the valve 39 to be opened and thereby permit liquid to escape from the liquid column into the cylinder 28 and reservoir 30.

70 During the time that the plunger 26 and piston 27 are moving under such pressure the spring 43 will hold the valve 39 closed until the end of the stem 40 engages the abutment 44.

75 As soon as the ram 13 of the press starts to ascend the pressure in the liquid column will be relieved and the pressure in the reservoir 30 acting upon the liquid in the cylinder 28 will move the piston 27 in the opposite direction and as soon as the end of the valve stem 40 moves out of engagement with the abutment 44 the valve 39 will close and will remain closed until the end of the plunger 26 engages the shoulder 45. At this time 80 pressure in the reservoir 30 upon the liquid in the cylinder 28 and in the plunger 26 will operate upon the valve 39 to open the same against the stress of the spring 43 and thereby permit liquid to flow back into the liquid column to replace the liquid which had previously escaped therefrom.

85 With this improved construction there is provided a combined shock absorber, relief and check valve as a unitary structure.

90 The variation in pressure will be compensated by varying the pressure on the column of liquid which in turn is effective on the piston 27 and the ratio of air pressure to the pressure obtained in the die cushion 22 is directly proportionate to the area of the piston 27 and the area of the plunger 26 which yields on a downward stroke of the press 95 and serves as a shock absorber.

100 The relief valve is associated with the plunger of the shock absorber and is not rendered active until the limit of the stroke of the shock absorbing piston has been reached. The relief valve which operates at the upper 105 end of the shock absorbing cylinder also serves as a check valve which permits the liquid to flow into the cylinder 22 to maintain the cylinder and the liquid column filled at all times.

110 While the preferred form of the invention 130

has been herein shown and described, it is to be understood that various changes may be made in the details of construction and in the combination and arrangement of the several parts, within the scope of the claims, without departing from the spirit of this invention.

What is claimed as new is:—

1. In a sheet metal press a pressure pad, means for maintaining a column of liquid for yieldingly resisting the movement of said pad in one direction, a shock absorber operated upon by said column of liquid for overcoming the initial resistance of the liquid upon said pressure pad, and a combined check and relief valve operatively connected with said shock absorber and automatically actuated at a predetermined time in the cycle of operation of said shock absorber to permit the escape of liquid from said column to relieve the pressure therein, the said valve being automatically opened at a predetermined time in the cycle of the return movement of said pressure pad to permit liquid to flow back into said column. 70
2. In a sheet metal press a pressure pad, means for maintaining a column of liquid for yieldingly resisting the movement of the pad in one direction, a shock absorber operated upon by said column under pressure of said pad for overcoming the initial resistance of the liquid to the said movement of said pad, a pressure accumulator reservoir for supplying resistance fluid to the shock absorber, a combined check and relief valve connected with the shock absorber, and means for positively opening said valve at a predetermined time in the cycle of operation of the shock absorber to permit liquid to escape from said column and into said reservoir, the said valve being automatically opened at another time in the cycle of operation of the shock absorber by pressure in said reservoir to permit escaped liquid to flow back into said column of liquid. 75
3. In a sheet metal press a pressure pad, means for maintaining a column of liquid for yieldingly resisting the movement of the pad in one direction, a pressure accumulator reservoir, a shock absorber between the said column and reservoir for overcoming the shock of the initial resistance pressure of said column upon said pad, means operating automatically at a predetermined time in the cycle of operation of the press for releasing some of the liquid from said column into said reservoir, and means controlled by the pressure in said reservoir for subsequently supplying said column of liquid with the quantity of liquid previously released therefrom. 80
4. In a sheet metal press, a pressure pad, means for maintaining a column of liquid for yieldingly resisting the movement of said pad in one direction, a pressure accumulator reservoir, a shock absorber intermediate said column and said reservoir and embodying a cylinder communicating with the reservoir, a piston movable in the cylinder, a plunger connected with the piston and movable in said column and upon which plunger the liquid in the column acts, a fluid passage through said plunger forming communication between said column and shock absorber, a valve in said passage, means for opening said valve to permit escape of liquid from said column, and means whereby the valve will be subsequently opened to permit return of liquid into said column. 85
5. In a sheet metal press, a pressure pad, means for maintaining a column of liquid for yieldingly resisting the movement of the pad in one direction, a pressure accumulator reservoir, means embodying a check and relief valve intermediate said column and reservoir for controlling the pressure in said column, and means operating to open said valve at a predetermined time in the cycle of operation of the press to permit some of the liquid in said column to escape into said reservoir, the pressure in said reservoir subsequently opening said valve to permit liquid to flow back into said column. 90
6. In a sheet metal press, a pressure pad, means for maintaining a column of liquid for yieldingly resisting the movement of said pad in one direction, a pressure accumulator reservoir, a shock absorber intermediate said column and reservoir for overcoming the shock of the initial resistance pressure of said column upon said pad, a combined check and relief valve connected with the shock absorber, means for automatically opening said valve to permit liquid to escape from said column into said reservoir, and means whereby the said valve will be subsequently operated to permit liquid to be delivered into the said column. 95
7. In a sheet metal press a pressure pad, means for maintaining a column of liquid for yieldingly resisting the movement of said pad in one direction, a pressure accumulator reservoir, a shock absorber intermediate said column and said reservoir and embodying a cylinder communicating with the reservoir, a piston movable in the cylinder, a plunger connected with the piston and movable in said column and upon which plunger the liquid in the column acts, a fluid passage through said plunger forming communication between said column and shock absorber, a valve in said passage, means for opening said valve to permit escape of liquid from said column, and means whereby the valve will be subsequently opened to permit return of liquid into said column. 100
8. In a sheet metal press a pressure pad, means for maintaining a column of liquid for yieldingly resisting the movement of said pad in one direction, a pressure accumulator reservoir, a shock absorber intermediate said column and said reservoir and embodying a cylinder communicating with the reservoir, 105
9. In a sheet metal press a pressure pad, means for maintaining a column of liquid for yieldingly resisting the movement of said pad in one direction, a pressure accumulator reservoir, a shock absorber intermediate said column and said reservoir and embodying a cylinder communicating with the reservoir, 110
10. In a sheet metal press a pressure pad, means for maintaining a column of liquid for yieldingly resisting the movement of said pad in one direction, a pressure accumulator reservoir, a shock absorber intermediate said column and said reservoir and embodying a cylinder communicating with the reservoir, 115
11. In a sheet metal press a pressure pad, means for maintaining a column of liquid for yieldingly resisting the movement of said pad in one direction, a pressure accumulator reservoir, a shock absorber intermediate said column and said reservoir and embodying a cylinder communicating with the reservoir, 120
12. In a sheet metal press a pressure pad, means for maintaining a column of liquid for yieldingly resisting the movement of said pad in one direction, a pressure accumulator reservoir, a shock absorber intermediate said column and said reservoir and embodying a cylinder communicating with the reservoir, 125
13. In a sheet metal press a pressure pad, means for maintaining a column of liquid for yieldingly resisting the movement of said pad in one direction, a pressure accumulator reservoir, a shock absorber intermediate said column and said reservoir and embodying a cylinder communicating with the reservoir, 130

a piston movable in the cylinder, a plunger connected with the piston and movable in said column and upon which plunger the liquid in the column acts, a fluid passage through said plunger forming communication between said column and shock absorber, a valve in said passage, means for opening said valve to permit escape of liquid from said column, and means whereby pressure in said reservoir will subsequently open said valve to permit return of liquid into the said column.

9. In a sheet metal press a pressure pad, means for maintaining a column of liquid for 15 yieldingly resisting the movement of said pad in one direction, a pressure accumulator reservoir, a shock absorber intermediate said column and said reservoir and embodying a cylinder communicating with the reservoir, 20 a piston movable in the cylinder, a plunger connected with the piston and movable in said column and upon which plunger the liquid in the column acts, a fluid passage through said plunger forming communication between 25 said column and shock absorber, a valve in said passage, means arranged in the path of movement of a portion of said valve with said plunger for opening the valve to permit escape of liquid from said column, and means 30 for subsequently opening said valve to permit return of liquid into said column.

10. In a sheet metal press a pressure pad, means for maintaining a column of liquid for 35 yieldingly resisting the movement of said pad in one direction, a pressure accumulator reservoir, a shock absorber intermediate said column and said reservoir and embodying a cylinder communicating with the reservoir, 40 a piston movable in the cylinder, a plunger connected with the piston and movable in said column and upon which plunger the liquid in the column acts, a fluid passage through 45 said plunger forming communication between said column and shock absorber, a valve in said passage, means arranged in the path of movement of a portion of said valve with 50 said plunger for opening the valve to permit escape of liquid from said column, means for arresting the return movement of the plunger, 55 and means whereby said valve will be automatically opened after said plunger has been arrested, to permit liquid to be delivered into 60 said column.

11. In a sheet metal press a pressure pad, 55 means for maintaining a column of liquid for yieldingly resisting the movement of said pad in one direction, a pressure accumulator reservoir, a shock absorber intermediate said column and said reservoir and embodying 60 a cylinder communicating with the reservoir, a piston movable in the cylinder, a plunger connected with the piston and movable in said column and upon which plunger the liquid in the column acts, a fluid passage 65 through said plunger forming communica-

tion between said column and shock absorber, a valve in said passage, means arranged in the path of movement of a portion of said valve with said plunger for opening the valve to permit escape of liquid from said column, 70 means for arresting the return movement of the plunger, and means whereby the pressure in said reservoir will operate to open said valve when said plunger has been thus arrested, to permit liquid to be delivered into 75 said column.

In testimony whereof we have signed our names to this specification, on this 4th day of April, A. D. 1930.

RUDOLPH W. GLASNER.
